UNITED STATES PATENT OFFICE.

WILLIAM T. SHERER, OF CHICAGO, ILLINOIS.

DISPLAY-COUNTER.

1,380,161.

Specification of Letters Patent. Patented May 31, 1921.

Application filed April 12, 1920. Serial No. 373,108.

To all whom it may concern:

Be it known that I, WILLIAM T. SHERER, a citizen of the United States, residing at Chicago, in the county of Cook and State 5 of Illinois, have invented a certain new and useful Improvement in Display-Counters, of which the following is a specification.

My invention relates to display counters adapted for use in grocery stores and the 10 like where goods for sale are kept in drawers and where it is desirable to have samples of the goods in question on display in immediate proximity to the drawers in which they are kept. One object of my 15 invention is to produce such a display counter. Another object of my invention is so to display the goods that they may be observed, examined, and indicated by the customer with the least possible effort.

20 My invention is illustrated more or less diagrammatically in the accompanying drawings, wherein:

Figure 1 is a front view of my counter;

Fig. 2 is a vertical section on the line 2—2 25 of Fig. 1 on an enlarged scale;

Fig. 3 is a vertical section on the line 3—3 of Fig. 1 on an enlarged scale;

Fig. 4 is a horizontal section on the line 4—4 of Fig. 1 on an enlarged scale.

30 Like parts are indicated by like characters throughout.

A is my display counter subdivided into the joined vertical sections A¹ by the vertical partitions a¹⁰ a¹⁰. Each of these carries 35 in its forward side the display pocket A² adjacent the top of the counter, and in its rear the drawers A³.

The display pockets are subdivided into the smaller pockets A⁴. The number of 40 these pockets in the front of any given vertical division of my counter corresponds to the number of drawers in the rear of the same division. Thus, if there are three subdivisions in any given display pocket there 45 will be three drawers in the rear of the section in which that pocket is mounted.

The use and operation of my invention are as follows:

When the counter as shown in Fig. 1 is 50 in use, the goods for sale are displayed in the transparent display pockets, and goods identical with those displayed are contained

in the drawers in the rear of the pocket. A customer deciding to purchase a certain article will look along the counter and will 55 indicate to the salesman the article desired. The salesman will then secure the article in question from the drawer immediately adjacent and in the rear of the pocket.

Where it is necessary for the salesman to 60 go to some other place to procure the other article there is always the question in the mind of the purchaser whether he is being furnished with the goods which he has indicated. When, however, he indicates the 65 goods which he desires in front of the counter and the salesman procures those goods from a drawer immediately behind the display pocket, the customer is usually satisfied that he is receiving exactly what he has 70 asked for.

I have arranged all of the display pockets of my present counter in a row near the top of the counter thus it is not necessary for the customer to back away from the 75 counter to look at the lower rows, and I do not have any glass along the lower part of the counter where it is likely to be injured or broken.

I claim:

1. As a new article of manufacture, a display counter subdivided into vertical sections, having a row of superimposed drawers, in the rear of each section and a group of separate display pockets arranged on the 85 front of each section, in horizontal alignment, adjacent but beneath the top of the counter, the number of pockets in each section equaling the number of drawers therein.

2. As a new article of manufacture, a display counter subdivided into vertical sections, having a plurality of superimposed drawers in the rear of each section, and a display pocket on the front of each section, adjacent the top thereof, said display pocket 95 being sub-divided into a plurality of separate display spaces, the number of said spaces equaling the number of drawers in the section in which the display pocket is placed.

Signed at Chicago, county of Cook and State of Illinois, this 5th day of April, 1920.

WILLIAM T. SHERER.
